UNITED STATES PATENT OFFICE

153,786

DESIGN FOR A FLASK

Clay A. Gladstone, Los Angeles, Calif.

Application October 31, 1947, Serial No. 142,245

Term of patent 3½ years

(Cl. D58—6)

To all whom it may concern:

Be it known that I, Clay A. Gladstone, a citizen of the United States, residing in Los Angeles, in the county of Los Angeles and State of California, have invented a new, original, and ornamental Design for a Flask, of which the following is a specification, reference being made to the accompanying drawing, forming a part thereof.

Fig. 1 is a top plan view of a flask;

Fig. 2 is a front elevational view of the same; and

Fig. 3 is a side elevational view of the same, showing my new design.

The rear view of the flask is the same as the front view.

I claim:

The ornamental design for a flask, as shown and described.

CLAY A. GLADSTONE.
